Primary Examiner—Mitchell Siegel(57) CLAIM

The ornamental design for a golf iron head, as shown and described.

DESCRIPTION

FIG. 1 is an elevational view of the rear of a golf iron head; FIG. 2 is an inverted perspective view of the golf iron head of FIG. 1;

FIG. 3 is an elevational view of a second embodiment of the rear of a golf iron head;

FIG. 4 is an inverted perspective view of the golf iron head of FIG. 3;

FIG. 5 is an elevational view of a third embodiment of the rear of a golf iron head; and,

FIG. 6 is an inverted perspective view of the golf iron head of FIG. 5.

The broken lines shown in FIGS. 1, 2, 3, 4, 5, and 6 are for illustrative purposes only and form no part of the claimed design.
